(57) **CLAIM**

The ornamental design for a display panel or portion thereof with graphical user interface, as shown and described.

DESCRIPTION

The sole FIGURE is a front view of a display panel or portion thereof with graphical user interface, showing my new design.

The pair of evenly spaced broken lines depict the display panel or portion thereof and form no part of the claimed design. All other broken lines illustrate portions of the graphical user interface that form no part of the claimed design.
